UNITED STATES PATENT OFFICE.

EDMUND P. HADLEY AND CROFTON C. HOLDEN, OF LEOMINSTER, MASSACHUSETTS.

DESIGN FOR A JEWEL-CASE.

49,513.

Specification for Design. Patented Aug. 15, 1916.

Application filed June 19, 1916. Serial No. 104,622. Term of patent 3½ years.

To all whom it may concern:

Be it known that we, EDMUND P. HADLEY and CROFTON C. HOLDEN, said HADLEY a citizen of the United States, said HOLDEN being a subject of the King of Great Britain, both residing at Leominster, in the county of Worcester and State of Massachusetts, have invented a new, original, and ornamental Design for a Jewel-Case, of which the following is a specification, reference being had to the accompanying drawing, forming part of this specification, in which—

Figure 1 is a perspective view of a jewel case showing our new design, Fig. 2 is a front elevation thereof, and Fig. 3 is a plan view.

We claim:—

The ornamental design for a jewel case as shown.

In testimony whereof we have hereunto affixed our signatures.

EDMUND P. HADLEY.
CROFTON C. HOLDEN.
